DESIGN FOR A BILLFOLD

John P. Wege, West Bend, Wis., assignor to Amity Leather Products Co., West Bend, Wis., a corporation of Wisconsin

Application September 7, 1934, Serial No. 53,218

Term of patent 7 years

To all whom it may concern:

Be it known, that I, JOHN P. WEGE, a citizen of the United States residing at West Bend in the county of Washington and State of Wisconsin, have invented a new, original, and ornamental Design for Billfolds, of which the following is a specification, reference being had to the accompanying drawing, forming a part thereof.

In the drawing:

Fig. 1 is a front elevational view of a billfold showing my new design;

Fig. 2 is a view of the end of the billfold having the pocket flap and fastening tab; and

Fig. 3 is a view of the other end of the billfold.

I claim:

The ornamental design for a billfold as shown.

JOHN P. WEGE.
